(57) **CLAIM**

The ornamental design for an animal leash, as shown and described.

DESCRIPTION

FIG. 1 is a perspective view of my animal leash;
FIG. 2 is a front elevational view of my animal leash, the rear view being a mirror image of this view;
FIG. 3 is a right side elevational view of my animal leash, the left side view being a minor image of this view; and,
FIG. 4 is a top view of my animal leash, the bottom view being a mirror image of this view.
